UNITED STATES PATENT OFFICE

2,494,313

SOURCE TRANSFER SWITCH

Raymond N. Rowe, Plainville, Conn., assignor to
 The Trumbull Electric Manufacturing Company, Plainfield, Conn., a corporation of Connecticut

Application December 22, 1945, Serial No. 636,738

8 Claims. (CL 200—17)

1

My invention relates to switches capable of connecting a load to any one of several sources of current or vice versa connecting any one of several loads to a source of power.

The main object is to provide a switch capable of selectively connecting a load to any one of at least three sources of power.

The invention constitutes an improvement on the invention set forth in my application for United States Patent filed December 6, 1945, Serial Number 633,147, now Patent No. 2,457,497, Dec. 28, 1948, which serves to control two sources of power for a given load or vice versa, a single source selectively arranged to serve two load circuits.

For the safe control of power in such devices the switching mechanism should be of the quick make and break type and enclosed in a suitable receptacle or box with an external operating handle.

One object is to provide a switch of this character in which the parts of the switch contact mechanism are assembled as a unit and the parts of the actuating mechanism are assembled as a discrete unit and the two mechanism units are so constructed and assembled so that they are placed in operable connection by the mere closing of the box cover.

Another object is to provide a switch of this character in which the contacts are all mounted in the body of the box and the actuating mechanism is all mounted on the cover.

Another object is to provide a switch in which the operator is compelled to disconnect the circuits completely before he can complete other circuits.

Another object is to compel the operator to make a complete rotation of the actuating handle before he can change from one position to another.

Another object is to provide a switch in which the switch mechanism can be turned in either direction so that the circuits can be made or broken consecutively in either of two orders, i. e. a circuit can be completed from an "off" position by turning the handle either right or left handed and the circuit can be broken from an "on" position by turning the handle either to the right or to the left.

Another object is to provide a construction in which the operating handle can be locked with the switch circuits in any one of the several arrangements provided.

Improvements in details of the assembly will 53

2

be understood from the following description and the accompanying drawings.

Fig. 1 is a front view of one form of switch embodying my invention, the box being closed.

Fig. 2 is a side view and partial section of the switch.

Fig. 3 is a view showing the cover open with the switching parts mounted in the box and the actuating mechanism attached to the inside of the cover in the normal position.

Fig. 4 is a view of the actuating mechanism in the same position as in Fig. 3, parts being broken away.

Fig. 5 is a sectional view on the plane of the line 5—5 of Fig. 4.

Fig. 6 is a sectional view on the plane of the line 6—6 of Fig. 4.

Fig. 7 is a sectional view on the plane of the line 7—7 of Fig. 4.

Fig. 8 is a fragmentary view of parts of the actuating mechanism in the relative position they occupy when starting to throw the switch.

Fig. 9 is a fragmentary view of the parts in an intermediate position.

Fig. 10 is a view of the gear member of the actuating mechanism.

Fig. 11 is an edge and partial sectional view of the same.

Fig. 12 is a view of the cam member assembled with the lost motion device of the actuating mechanism but omitting the springs.

Fig. 13 is an edge and partial sectional view of the parts of Fig. 12.

Figs. 14, 15, 16 and 17 are diagrammatic views of the circuits in the respective positions of normal power connection, alternate power connection, emergency connection and an "off" position.

In the form shown the box has a body 20 and a cover 21 hinged to it at 22 and tightly secured by fastener 23 when in use as set forth and described in application Serial Number 619,998, filed October 3, 1945.

The contact making and breaking parts or switch per se may be of any suitable type with a rotatable central shaft 24 for the movable switch member supported in the body of the box and having an arm 25 by which the movable switch member may be rotated step by step in either direction and an insulating top plate 26.

A general type of switch which may be used is shown in my above-mentioned application S. N. 633,147, filed Dec. 6, 1945. Details of the preferred switching unit per se are shown and claimed in a later application, S. N. 652,586, filed

March 7, 1946, now Patent No. 2,465,933, Mar. 29, 1949.

The actuating mechanism is all carried by the cover and has a central shaft 27 rotatable in the bearing 28 which is secured to the cover 21. The shaft is held in the bearing by screws 29 which pass through a cap piece 30 into the outer end of the shaft. A disc 31 is secured to the inner end of shaft 27 by screw 32. This disc has a slot 33 to receive the stud 33' on the switch arm 25. This disc is guided at its periphery by brackets 34 carried by the cover. Inclined guides 35 assist in positioning the disc with respect to the switch arm when the cover is being closed. A stud 25' carried by arm 25 is provided to act as a stop against the top plate 26 in case pressure is applied to the arm.

The shaft 27 and disc 31 are rotated step by step by the quick make and break mechanism inside the cover when actuated by the rotation of the handle 40 on the outside. The latter has a shaft 41 mounted in the bearing 42 and having a pinion 43 on the inner end. This pinion meshes with an internal annular gear 44 inside the cover supported by a disc 45. The disc has a collar 46 rotatable on the shaft 27 and the periphery of the disc is secured to the annular gear.

A cam member 47 which may be formed of a number of plates secured together is secured to the disc 31 by a number of studs 48, 48, 48 and 49, 49, 49. The cam member has six cam projections corresponding to the number of circuit making and breaking positions the switch is intended to provide. Two rollers 50, 50 are provided, one on either edge of the cam member. These rollers are carried by arms 51, 51 pivoted at 52, 52 and the arms are biased by spring 53 so as to press the rollers against the opposite edges of the cam member and normally into the bottoms of the spaces between cam projections as shown in Fig. 4.

Between the disc 45 and the cam member 47 is located a lost motion device 54 which may be made up of a number of plates suitably secured together by studs 55, the ends of which extend into elongated slots 56 in the disc 45.

This lost motion device has three outwardly projecting segments 57, 57 adapted to move between adjacent studs 48, 48 but normally held midway as shown in Figs. 4 and 12 by the action of springs 58, 58. The lost motion device has three outwardly projecting lugs 59, 59 and the cam member 47 has three lugs 60, 60 projecting inwardly between lugs 59, 59 and the springs 58 are located in the spaces between adjacent lugs 59 and 60.

It will thus be seen that when the handle 40 is rotated it will rotate the annular gear 44 by means of the pinion 43. The lost motion device 54 will not move however until each stud 55 reaches one end or the other of its slot 56. When the device starts to rotate it compresses the springs 58 between lugs 59 and 60 so as to store up power. When the device 54 rotates sufficiently each segment 57 engages a stud 48 and starts the rotation of the cam member 47. This forces the rollers 50, 50 outwardly to the position of Fig. 8. As soon as the resistances of the rollers is overbalanced by the power stored by the compression of the springs 58, 58, the springs 58 and the spring pressed rollers 50, 50 suddenly advance the cam member 47 with the attached disc 31 and thus throw the switch forward or backward as the case may be through the angle of 60 de-

grees. By rotating the handle in the opposite direction the switch may be thrown in the opposite direction and so step by step in either direction by the rotation of the handle. The parts 5 of the lost motion device 54 may be held together by means of a cover plate 61 having key-hole shaped openings 61' to engage beneath the heads of studs 55.

The bearings 28 and 42 may be formed in a 10 single casting 62 which bears the indications as to the position of the switch contacts as shown in Fig. 1. Here is shown an indicator arrow carried by a disc 63 secured to the hub of the shaft 27 (Fig. 5). As the handle 40 must be given a 15 rotation of 360° in order to actuate the switch each step it is possible to lock the handle with the switch in any one of its six positions by passing a padlock or other locking device through the hole 64 in the handle and between the lugs 20 65 on the casting 62.

The wiring diagrams of Figs. 14, 15, 16 and 17 show the relative positions of the stationary and 25 movable contacts of a switch for a three wire system. Each dot and dash circle represents an insulating disc. Each black dot represents a stationary contact and each diamond represents a movable contact it being understood of course that the movable contacts are all carried by supports which rotate with the main shaft 24 of the switch. L1, L2 and L3 represent the contact terminals of the load circuit. S1A, S1B and S1C represent the contact terminals of what may be called the normal source of current. S2A, S2B and S2C represent the contact terminals of the alternate source. EA, EB and EC represent the emergency source. The heavy curved lines represent the jumper connections between the various contacts. In Fig. 17 it will be seen that no movable contact engages any stationary contact and each light circuit is open. With the switch in the normal "on" position of Fig. 14 the normal current flow is from S1A, S1B and S1C to L1, L2, L3 respectively. With the switch connected to 40 the alternate source of Fig. 15 the current flows from S2A, S2B and S2C to L1, L2 and L3 respectively.

With the switch in the Emergency position of Fig. 16 the current flows from EA, EB and EC to 50 L1, L2 and L3 respectively. The connection of the various signal light circuits is obvious from the diagrams.

Although the switch is primarily intended to 55 operate with a quick make and break action it will be seen that the connections are such that the switch can be actuated to open and close the circuits by a positive drive even if all the springs should be broken.

I claim:

1. A transfer type switch comprising a rotatable switch member rotatable in either direction, a rotatable throwing member having a number of uniform recesses and cam projections occupying the entire periphery of the throwing member, spring pressed rollers coacting with said projections and recesses to provide a continuous series of switching positions, a connection between said throwing member and said switch member, a rotatable handle movable in either direction, a lost motion connection between said handle and said throwing member geared so that said handle may be rotated more than 360° before it will rotate said throwing member from one switching position to either the preceding or succeeding position.
2. Transfer switch mechanism including a ro-

5 rotatable cam member having a series of uniform alternate recesses and projections arranged around its entire periphery, a rotatable actuating handle, lost-motion and spring take-up means of connection between said handle and said cam member and a pair of opposed spring pressed members engaging the periphery of said cam member for causing its sudden rotation free from control of the operator.

3. In a transfer type electric switch, a rotatable switch member having "off" position and "on" positions alternating with the "off" positions, a rotatable cam member, means of connection between said cam member and said rotatable switch member, a rotatable pick-up member having a lost-motion and spring connection with said cam member, a rotatable gear member having a two-way lost motion connection with said pick-up member and a handle member geared to said gear member, said cam member having uniform recesses and projections alternating with the recesses and a pair of opposed spring pressed rollers coacting with the projections and recesses of the cam member for rotating the cam member step-by-step when the handle is rotated.

4. In an electric switch, a switch member rotatable step by step, actuating mechanism for said switch member comprising a cam member having a number of identical cam shoulders with intervening recesses extending 360° around said cam member, means for connecting said cam member with said switch member, a gear member, a rotatable handle having a pinion for driving said gear member, a lost motion device interposed between said gear member and said cam member and having a stud and elongated slot connection with said gear member and having a reversible lost motion connection including throwing springs with said cam member, and a pair of opposed spring pressed members coacting with the shoulders and recesses of said cam member to cooperate with the throwing springs in rotating said cam member and said switch member out of control of the operator when said handle is rotated.

5. A transfer switch having a plurality of "on" positions and an equal number of "off" positions alternating therewith, a rotatable switching member movable step by step in either direction between stations corresponding to these positions, an actuating handle rotatable freely over at least 360°, and a connection between said handle and said rotatable switching member whereby the switch member may be rotated back and forth step by step as the handle is rotated, consecutive movements in either direction requiring the handle to be rotated at least 360°.

6. In a transfer electric switch, a plate rotatable in either direction and having a number of projections alternating with recesses, each pro-

jection having a rounded end and each projection being shaped like all the other projections, a spring pressed roller coacting with said projections and recesses as the plate is rotated, a gear coaxial with said plate, lost-motion means of connection between said gear and said plate, a handle having a pinion meshing with said gear and rotatable in either direction, the ratio of the pinion to the gear being such that for a single rotation of said handle and pinion the plate is turned through an angle equal to the angular spacing of the projections on the plate, and a rotor actuated by said plate.

7. In an enclosed switch including a receptacle having a cover, a rotor element mounted in the receptacle and having a crank arm, a plate rotatably carried by the cover and having a number of recesses in its periphery, a pair of rollers spring-pressed against the periphery of said plate, a gear coaxial with said plate, lost motion means of connection including spring means between said gear and said plate, a handle rotatably carried by said cover and having a pinion on the inner end meshing with said gear and means for connecting said plate with said crank arm when the cover is closed.

8. A switch for transferring a load from one source to another comprising means having a plurality of stationary switch contact stations with "off" stations alternating with the contact stations and a rotor member having spaced contacts adapted to coact with the stationary contact stations and means for rotating said rotor step by step in either direction, said means including a control cam member having alternating projections and recesses uniformly located around the entire periphery of the cam member, a spring-pressed member coacting with the periphery of the cam member to hold it yieldingly in "on" or "off" position, a gear member having a limited lost motion connection with said cam member and a manually rotatable pinion meshing with said gear member, the ratio of the pinion to the gear member being such as to ensure rotation of the cam member from an "off" station to an "on" station or vice versa when the pinion is turned 360° in one direction or the other.
